UNITED STATES PATENT OFFICE.

STANTON F. BAKER, OF REYDEL, ARKANSAS.

CAP FOR FILLING-OPENINGS OF AUTOMOBILE-RADIATORS.

1,281,481.

Specification of Letters Patent. Patented Oct. 15, 1918.

Application filed July 9, 1918. Serial No. 244,025.

To all whom it may concern:

Be it known that I, STANTON F. BAKER, a citizen of the United States, residing at Reydel, in the county of Jefferson, State of Arkansas, have invented a new and useful Cap for Filling-Openings of Automobile-Radiators; and I do hereby declare the following to be a full, clear, and exact description of the invention, such as will enable others skilled in the art to which it appertains to make and use the same.

This invention relates to an improved cap or cover adapted for use in connection with filling openings of automobile radiators, preferably of the Ford type.

Heretofore it has been found difficult to ascertain when the water in the radiator is excessively warm or hot. Furthermore when the radiator is hot, it is very annoying to unscrew the old style hot cap.

The present invention aims to avoid these disadvantages by providing a perforated cap, so that when the automobile is stopped, and in case the water is hot, the steam will percolate through the perforations, thereby indicating or notifying the necessity of refilling the radiator with a fresh supply of cold water.

The invention further aims to provide a hinged cap, whereby the cap may be easily swung open, to avoid unscrewing.

The invention further aims to construct one end of one of the hinged members in a catch to engage a depression in the exterior of the flanged wall of the filling opening, to hold the cap closed.

The invention further aims to construct one of the hinge members in the form of a spring which is normally substantially straight when the cap is open, so as to exert constant pressure on the cap to hold it tight when closed.

The invention further aims to provide a cap, which may be applied to a radiator filling opening at the time of constructing the radiator or may be applied to the filling openings of radiators now in use.

The invention further aims to provide means for holding a brass composition or other suitable washer between the cap and the flange of the filling opening.

The invention comprises further features and combination of parts as hereinafter set forth shown in the drawings and claimed.

In practical fields the details of construc-

tion may necessitate alterations falling within the scope of what is claimed.

In the drawings:—

Figure 1 is a view in front elevation of an automobile radiator, showing the cap as applied to the filling opening.

Fig. 2 is a vertical sectional view through the filling opening on line 2—2 of Fig. 1.

Fig. 3 is a plan view of Fig. 2.

Fig. 4 is a view in side elevation of a filling opening showing a modified form of cap.

Fig. 5 is a plan view of Fig. 4.

Fig. 6 is a sectional view on line 6—6 of Fig. 5.

Referring more especially to the drawings 1 designates a portion of a radiator having the usual filling opening 2 provided with a marginal flange 3, the inner circumference of which near the upper end is provided with a ledge or rib 4, which is annular.

Mounted upon the upper end of the flange of the filling opening is a cap 5, provided with a downwardly extending extension annular flange 6, between which and the ledge 4 any suitable washer 7 constructed of any suitable material, preferably brass composition is interposed, in order to provide a tight joint between the cap and the ledge.

By means of the hinge connection 8, the cap is hingedly mounted on the flange of the filling opening. One member of this hinge as at 9 is integrally carried by the flange of the filling opening, while the other member 10 is in the form of an elongated spring strip, which is riveted or otherwise fastened to the cap. This spring strip extends entirely across the upper surface of the cap, and has its extremity bent to form a lug 12 to engage a suitable depression 13 in the front part of the upper end portion of the flange 3 of the filling opening, to hold the cap closed.

The extremity 14 beyond the lug 12 is designed to be engaged by the finger, so as to disengage the lug from the depression, when it is desired to open the cap. The spring strip when the cap is opened tends to become substantially straightened at the point indicated by the numeral 15, so that when the cap is closed a constant pressure on the washer or gasket 7 is exerted, to insure a tight joint. This joint is maintained materially since the cap as indicated at 16 near the marginal edge of the cap is spaced from the upper edge of the

- annular flange 3. The cap is curved or convexed as shown, and is provided with a plurality of perforations 17, through which the steam percolates in case the water in the 5 radiator is hot, thereby indicating or notifying that it is necessary to refill the radiator with a fresh supply of cold water. In Figs. 4, 5 and 6, instead of mounting the cap on the flange of the filling opening direct, 10 the cap is hingedly mounted as at 8^a on a ring bushing 18, which is angular in cross section. This bushing is threaded into the usual flange 3 of the filling opening. In this method of construction, it is obvious 15 that the cap may be applied to flanged filling openings of radiators now in use, while in Figs. 1, 2 and 3 the cap is especially designed to be constructed at the time of constructing the radiator and its filling opening. 20 In Figs. 4, 5 and 6 the annular ledge 4^a which is similar to the ledge 4 in Fig. 2, is carried by the bushing 18, so that the gasket or washer may fit between the ledge and the extension flange 6. The cap in Fig. 6 is also spaced 25 as at 16 from the upper face of the bushing. The cap in Fig. 6 also has perforations, and the spring strip 10 of the hinge 8^a performs the same functions as the spring strip 10 of the hinge 8 in Fig. 2.
- 30 The invention having been set forth what is claimed as new and useful is:—
1. The combination with a flanged filling opening, of a cap engaging the flange of the filling opening, a hinge hingedly connecting the cap to the flange, one member of the hinge being in the form of a spring strip extending across the top of the cap and being connected thereto and having its end oppo-

site the hinge terminating in a latching lug, means on the flange of the filling opening to 40 receive said latching lug.

2. The combination with a flanged filling opening, of a cap engaging the flange of the filling opening, a hinge hingedly connecting the cap to the flange, one member of the hinge being in the form of a spring strip 45 extending across the top of the cap and being connected thereto and having its end opposite the hinge terminating in a latching lug, means on the flange of the filling open- 50 ing to receive said latching lug, and means to afford a gasket tight joint for the cap, said cap having perforations.

3. The combination with a flanged filling opening, of a closure for said flanged filling 55 opening, said closure comprising a bushing detachably engaging said flange of the opening and a cap having perforations, a hinge connecting the cap to the bushing, one member of the hinge being in the form of a 60 spring strip extending across the top of the cap and being secured thereto and having its end opposite the hinge terminating in a latching lug, the flange of the filling opening having a depression to receive said 65 lug, a gasket tight joint between the bushing and the cap, said spring strip having means to exert constant pressure on the gasket tight joint.

In testimony whereof I have signed my 70 name to this specification in the presence of two subscribing witnesses.

STANTON F. BAKER.
